TION OF DELAWARE

PROCESS FOR THE PYROLYTIC CONVERSION OF NORMALLY GASEOUS ALIPHATIC
HYDROCARBONS

Application filed May 24, 1928. Serial No. 280,331.

This invention relates to improvements in processes for the thermal decomposition of gaseous hydrocarbons such as occur in natural gas and the like.

5 The primary object of the invention is to furnish a process in which light hydrocarbons such as occur in natural gas may be converted into heavier hydrocarbons of the aromatic series.

10 Another object of the invention is to provide a process designed to crack natural gas or the like for reforming the gas and producing substantial quantities of liquid hydrocarbons.

15 A still further object is to furnish a process in which substantially pure natural gas constituents such as ethane, propane, and butane, may be reformed and partially converted into liquid hydrocarbons.

20 It is also an object of the invention to provide a system in which gaseous hydrocarbons after a decomposition treatment may be separated into residue gas and liquid hydrocarbons, said residue gas being recycled for the purpose of decomposing and extracting from the same, additional amounts of liquid hydrocarbons.

25 With the foregoing objects outlined and with other objects in view which will appear as the description proceeds, the invention consists in the novel features hereinafter described in detail, illustrated in the accompanying drawings and more particularly pointed out in the appended claims.

30 Referring to the drawings, Fig. 1 is a diagrammatic elevation of an apparatus suitable for use in performing the process. Fig. 2 is a similar view of a modified heating device for use in such system.

35 The gas to be treated, whether formed of one or more of the lighter hydrocarbon constituents of natural gas, enters the system at the point A' through a suitable pressure regulator and meter B and passes through the pipe

40 C to the heat exchanger D. From the latter the gas passes through heating coils F in a suitable furnace P and flows from the coils through a pipe G into the reaction chamber H. In the coils F the gas is heated to a temperature just below the reforming tempera-

ture, and in G it is heated to the reforming temperature. In the reaction chamber the gas is held at the reforming temperature the necessary length of time to cause the desired conversion.

45 From the reaction chamber the reformed gas and the liquid hydrocarbons produced are sent through a pipe H¹ into the heat exchanger D where such material loses part of its heat to the untreated gases passing by way of pipe C and E to the heating coils F. The treated gases leave the heat exchanger by way of pipe H² and flow through a scrubber K of any desired character and from the latter the treated material passes through a pipe H³ into a benzol recovery plant L, in which the liquid hydrocarbons are separated from the reformed gas and discharged by way of outlet L¹.

50 Some of the reformed gases pass off by way of the pipe J to any suitable point of disposal and the remainder of the reformed gases are recycled through a conduit L², which leads the same through any suitable form of metering device A, back to the untreated gas line C.

55 It will be understood that valves are arranged in the pipe lines at the desired points to properly control the operations.

60 The tubes F and G are heated by products of combustion from gas burned in a combustion chamber M, and the products of combustion after passing through the furnace P escape to the atmosphere through the stack N.

65 When this process and apparatus are employed in the treatment of substantially pure components (propane, for instance,) it differs from other processes in that relatively fixed temperatures and velocities may be used.

70 In a process using a mixture of gases, say, ethane, propane, and butane, the synthesis is carried out at a temperature and time of exposure which will be an average of those most suitable for each individual component.

75 The condition suitable for one component gas such as propane, can be easily determined and then used for all future operations.

80 Regardless of whether a single component or a multi-component gas is treated, the reaction chamber H should be maintained at a 85 temperature just below the reforming tempera-

90

95

100

temperature within a range of 1250° F. to 1750° F. and the time of exposure of the products of the reaction should come within a range of 0.002 minutes to 10 minutes depending upon the temperature maintained, the character of the gas treated, and the products desired. Conditions of this character will permit the production of substantial quantities of liquid hydrocarbons, and by substantial quantities is meant at least .5 of a gallon to each 1000 cubic feet of gas treated.

The apparatus illustrated is preferably used for the treatment of hydrocarbon gases lighter than pentane, although there may be traces of the latter in the gas without any deleterious effect on the process.

The recycling step of the process may be used when a single component gas is treated or when a multi-component gas is treated, but it is preferably used when multi-component gases are subjected to the process.

When multi-component gases are treated, such as butane and propane, or butane, propane, and ethane, the recycling will allow some or all of the gas to be twice subjected to decomposing conditions and it has been found that this permits the production of larger quantities of liquid hydrocarbons.

Instead of using the heating means shown at the left hand side of the reaction chamber in Fig. 1, it is obvious that the gases to be processed may be heated in various ways and by any other suitable means. In Fig. 2 another modification of the heating means is disclosed. In this assembly a combustion chamber A^x is heated by a gas burner or the like. From the combustion chamber, the products of combustion flow through the heating chamber B^x to the stack H^x.

A coil C^x is arranged in the furnace and is connected by pipes D^x to the heating medium space I^x of the reaction chamber E^x. Tubes K^x pass through the reaction chamber from top to bottom and convey through the latter the gases to be treated, which enter through F^x and discharge through G^x.

By arranging a pump or the like L^x in one of the pipes D^x, an inert gas used as a heating medium for the reaction chamber may be circulated and in this way the temperature in the reaction chamber may be properly or accurately maintained.

The heating apparatus used in Fig. 1, and that of Fig. 2, have two things in common, viz.—a graduated control of heat application and complete freedom from contamination by any atmosphere foreign, or extraneous, to that of the gases under treatment.

The relation between temperature and exposure time for gases consisting largely of propane and butane has been determined, and is embodied in the following empirical formula,

$$T = 1245 - 180 \log_{10} t$$

wherein T=cracking temperature in degrees

Fahrenheit and t =time in minutes during which the gas is maintained at the temperature T, subsequent to a rapid heating to that temperature, with rapid cooling upon expiration of cracking period t . A several fold increase in exposure time above that calculated by the formula results in little increase in yield of volatile oils, but tar and carbon formation are thereby increased and the gas depleted in calorific value. Gases whose vapor pressures fall between 25 to 500 pounds per square inch have been found to respond successfully to the process treatments described above, but the invention is not limited to such gases. The pressure range mentioned, however, has the advantage that it enables the process treatment to take place substantially under atmospheric pressure throughout.

In regard to said formula, it may be stated that experiments were conducted with the object of determining the rôle of cracking time as well as temperature in producing an optimum yield of benzol. A gas of the composition

	Per cent
Methane	18.6
Propane	44.7
Butane	36.7

was submitted to cracking in a non-catalytic silica tube under conditions suitable for the production of benzol. The experiments were conducted at atmospheric pressure and the carbon, tar, benzol and gases were separately measured. The effect of time and temperature on benzol yield is shown in the following table, in which time is expressed in minutes and benzol yield in gallons per thousand cubic feet of gas:

Table.—Effect of time of cracking on benzol yield at several temperatures

Time	Yield	
1292° F.	.5	110
	1.1	1.7
	3.5	1.8
1382° F.	.28	1.8
	.38	2.1
	2.6	2.1
1562° F.	.012	1.7
	.031	1.9
	.066	1.8
1742° F.	.003	2.1
	.006	1.9

At a given temperature, the yield of benzol was observed to increase gradually as the cracking time increased, until a virtually maximum yield was developed. A several fold increase in time beyond the minimum necessary to develop a virtually maximum yield caused little change in benzol yield, but

tar formation was increased, of necessity through depletion of the gas. The increase in temperature increased the reaction velocity without greatly influencing the sequence of changes taking place during cracking. The maximum yield of benzol was roughly constant throughout the rather wide temperature range studied within the time range appropriate to and unique for each temperature. The data of the table show the minimum time required to obtain a substantially optimum yield of benzol at several temperatures within a rather wide range. The values are approximately 0.5 minutes at 1292° F., 0.2 minutes at 1382° F., 0.012 minutes at 1562° F., and somewhat less than 0.003 minutes at 1742° F.

These values may be used to determine a time-temperature relation which is expressed in a compact form by the equation

$$T = 1245 - 180 \log_{10} t,$$

in which "T" is temperature in degrees Fahrenheit, and "t" is time in minutes. The time given by the formula is a minimum value for the formation of a substantially maximum yield of benzol.

In practice, a reaction time as much as several fold greater may be used without loss in benzol yield. Since the literature shows that the time consumed by the initial decomposition of gaseous paraffins to form gaseous olefines is only a small fraction of the total time found to be required for forming a yield of benzol, it is obvious that the same time-temperature relation is applicable to the treatment of gaseous olefines to form benzol and to all the simpler paraffins which decompose into gaseous paraffins and gaseous olefines. Methane, because of its great stability to heat is not converted into benzol under the above mentioned time-temperature conditions.

In view of the foregoing it is believed that the steps of the process and details of the apparatus may be clearly understood by those skilled in the art and familiar with such processes and apparatus and that changes may be made in the details disclosed without departing from the spirit of the invention as expressed in the claims.

What is claimed and desired to be secured by Letters Patent is:

1. In a continuous process for the pyrolytic conversion of normally gaseous aliphatic hydrocarbons to crude benzol, rapidly heating said gaseous hydrocarbons to reforming temperatures between 1250 and 1750° F. in a passageway of restricted cross-sectional area, passing the heated gaseous hydrocarbons into an enlarged zone, maintaining without any addition of heat, the heated gaseous hydrocarbons in the said zone at the reforming temperature for an interval of time

substantially as expressed by the formula

$$T = 1245 - 180 \log_{10} t,$$

where "T" is the temperature in degrees Fahrenheit, and "t" is the time in minutes, and then separating the crude benzol so produced.

2. In a continuous process for the pyrolytic conversion of normally gaseous aliphatic hydrocarbons to crude benzol, rapidly heating said gaseous hydrocarbons to reforming temperatures between 1250 and 1750° F. in a passageway of restricted cross-sectional area, passing the heated gaseous hydrocarbons into an enlarged zone, maintaining without any addition of heat the heated gaseous hydrocarbons in said zone for an interval of time substantially as expressed by the formula

$$T = 1245 - 180 \log_{10} t,$$

wherein "T" is the temperature in degrees Fahrenheit, and "t" is the time in minutes, then partially cooling the effluent gases from said zone by indirect heat exchange with the inlet gases to said passageway, and finally separating the crude benzol so produced.

3. In a continuous process for the pyrolytic conversion of normally gaseous aliphatic hydrocarbons to crude benzol, rapidly heating said gaseous hydrocarbons to reforming temperatures between 1250 and 1750° F. in a passageway of restricted cross-sectional area, passing the heated gaseous hydrocarbons into an enlarged zone, maintaining without any addition of heat, the heated gaseous hydrocarbons in the said zone at the reforming temperature for an interval of time substantially as expressed by the formula

$$T = 1245 - 180 \log_{10} t,$$

wherein "T" is the temperature in degrees Fahrenheit, and "t" is the time in minutes, then separating the crude benzol so produced, and controllably returning portions of the residual cracked gas to the inlet stream of gaseous hydrocarbons entering said passageway.

4. In a continuous process for the pyrolytic conversion of normally gaseous aliphatic hydrocarbons to crude benzol, rapidly heating said gaseous hydrocarbons to reforming temperatures between 1250 and 1750° F. in a passageway of restricted cross-sectional area, passing the heated gaseous hydrocarbons into an enlarged zone, maintaining without any addition of heat, the heated gaseous hydrocarbons in the said zone at the reforming temperature for an interval of time substantially as expressed by the formula

$$T = 1245 - 180 \log_{10} t,$$

wherein "T" is the temperature in degrees Fahrenheit, and "t" is the time in minutes, partially cooling the effluent gases from said zone by indirect heat exchange with the inlet gaseous hydrocarbons to said passageway, separating the crude benzol so produced from

4

1,847,257

the residual cracked gas, and controllably returning portions of the residual cracked gas to the inlet stream of gaseous hydrocarbons entering said passageway.
